CLAIM

The ornamental design for a footwear as shown and described.

DESCRIPTION

FIG. 1 is a front, top and left side perspective view of footwear according to the new design;

FIG. 2 is a front side view thereof;

FIG. 3 is a back side view thereof;

FIG. 4 is a left side view thereof;

FIG. 5 is a right side view thereof;

FIG. 6 is a top view thereof;

FIG. 7 is a bottom view thereof; and,

FIG. 8 is a back, bottom, and right side perspective view thereof.

The broken lines in the drawings show portions that form no part of the claimed design.

1 Claim, 8 Drawing Sheets
